UNITED STATES PATENT OFFICE.

JOHN J. SMILEY, OF LOCKLAND, OHIO, ASSIGNOR TO THE PHILIP CAREY MANUFACTURING COMPANY, OF LOCKLAND, OHIO, A CORPORATION OF OHIO.

READY-MADE ROOFING.

1,018,524.

Specification of Letters Patent.

Patented Feb. 27, 1912.

Application filed February 28, 1908. Serial No. 418,194.

To all whom it may concern:

Be it known that I, JOHN J. SMILEY, a citizen of the United States, residing at Lockland, in the county of Hamilton and 5 State of Ohio, have invented certain new and useful Improvements in Ready-Made Roofing, of which the following is a specification.

My invention relates to roofing material, 10 its object being to strengthen the lap-extending longitudinally along the edge of the sheet, this invention consisting in providing a strip of roofing made up of a composition body and a woven strengthening layer im- 15 posed thereon and partially embedded therein, and overlapping and folded upon the body to form a nailing lap and a covering lap with an under-folded extension to the nail- 20 ing lap, whereby the strength of the nailing lap is increased and the durability of the 25 edge of the roofing, constituted by the nailing lap, is increased.

In the drawing: Figure 1 is a sectional perspective view showing the roofing in place 25 on the roof, part of the seam covering lap being raised. Fig. 2 is a perspective view illustrating a modification. Fig. 3 is a sectional view illustrating my invention, the nail covering lap being raised. Fig. 4 is a 30 sectional view showing the positions of the parts when the seam is finished.

The roofing is made up of the body 1 of cement, the essential qualities of which are 35 viscousness, to cause it to adhere to the woven strengthening layer 2, and pliability, to form a roofing sheet that may be conveniently rolled up and handled. The woven strengthening layer is composed of burlap, which, at one edge 3 of the sheet, terminates 40 coincident with the cement body, but at the other edge of the sheet continues past the cement body, and, being partially embedded in the cement body to within the proximity of this second mentioned edge, diverges 45 therefrom at 4, is continued separate from the body portion past the edge thereof, then folded under upon itself at 5, back close to the region of its divergence from the body portion, then folded forward at 6, and then 50 again folded under upon itself at 7, this last fold 7 being coincident with the edge 8 of the cement body, and the layer 9 being continued backward, preferably, past the region of the divergence 4 and second folding 6 55 thereof, and terminating at 10. This last

layer 9 thus lies directly on the cement body throughout the region near its edge 8 and forms a reinforcement therefor, so that when the nails 11 are driven through it a secure holding is effected, and, due to the 60 fold 7 coming coincident with the edge 8, also forms a durable edge for the roofing sheet. The roofing sheet is preferably completed by adding on the lower side of the cement body, a layer 12 of compact material, 65 such as paper or woolen felt, this layer coming next to the roof boards 13, into which the nails 11 are driven. The roofing sheet is beveled near both edges 3 and 8 to decrease the bulkiness of the seam formed by overlapping the sheets, and when the nails have been driven through the nailing flap between the folds 6 and 7, the part of the woven strengthening layer between the point of divergence 4 and fold 6, which is folded 75 at 5 and thus forms the covering flap, is secured down over the heads of the nails and over the nailing flap and to the adjacent sheet with which the seam is made, this covering flap being thus secured by a suitable 80 cement which is supplied in sufficient quantity to fill up the meshes of the woven strengthening layer throughout the region of the nail covering flap, and, this cement being of material of a character similar to 85 that composing the cement body of the roofing sheet, a practically continuous covering is thus effected.

When the layer 9 is continued back as far as the joint 10, a seam 14 may be run along, 90 passing through the main body part of the woven strengthening layer and through this layer 9 near its termination 10, before the woven strengthening layer is applied to the cement body, this construction being illustrated in Fig. 2 of the drawing. This seam 14 is advantageous in handling the strengthening layer before it is applied to the cement body during the manufacture of the roofing, and also adds to its strength after the roofing is completed, in that it reinforces the connection of the strengthening layer 2 with the cement body 1 in the region of their divergence by binding the upper main body part of the woven strengthening layer to the lower layer 9, and thus constituting for all practical purposes a continuous superimposed strengthening layer from edge to edge of the roofing sheet, but allowing of 105 the formation of the diverging covering lap. 110

This secure fastening of the woven strengthening layer to the cement body, and the durable edge presented by the fold 7, being advantageous in that they render the roofing 5 more durable when it is being handled between the time of its completion and the time it is applied to the roof, assume especial importance in cases where the roofing must be transported a considerable distance and 10 exposed to rough handling which would damage the edges and loosen the strengthening layer from the cement body, and by giving additional thickness to the nailing flap, the security of the fastening is increased.

15 Having fully described my invention, what I claim as new and desire to secure by Letters Patent is:

1. In ready made roofing, comprising a cement body portion and a superimposed 20 woven strengthening layer partially embedded therein, which diverges therefrom and is folded upon itself to form a nail and seam covering flap, and again folded to form, in conjunction with the cement body, 25 a nailing flap, an additional under-folded layer to the part of the woven strengthening layer which is comprised in the nailing flap and extends back past the line of origin of the covering flap, whereby a folded edge is 30 brought substantially coincident with the edge of the cement body, and whereby additional thickness and strength are provided for the nailing flap, substantially as and for the purposes specified.
- 35 2. In ready made roofing, comprising a cement body portion and a superimposed woven strengthening layer partially embedded therein, which diverges therefrom and

is folded upon itself to form a nail and seam covering flap, and again folded to form, in 40 conjunction with the cement body, a nailing flap, an additional under-folded layer to the part of the woven strengthening layer which is comprised in the nailing flap, whereby a folded edge is brought substantially coincident with the edge of the cement body, and whereby additional thickness and strength are provided for the nailing flap, 45 said additional under-folded layer being extended back past the line of origin 50 of the covering flap and being attached by a seam to the main part of the woven strengthening layer in the region near its divergence from the cement body, substantially as and for the purposes specified. 55

3. In ready made roofing, comprising a cement body portion and a superimposed woven strengthening layer partially embedded therein, which diverges therefrom and is folded upon itself to form a nail and seam 60 covering flap, and again folded to form in conjunction with the cement body, a nailing flap, an additional under-folded layer to the part of the woven strengthening layer which is comprised in the nailing flap, 65 whereby a folded edge is brought substantially coincident with the edge of the cement body, and whereby additional thickness and strength are provided for the nailing flap, substantially as and for the purposes specified. 70
